Primary Examiner — Andrew Kerr*Assistant Examiner* — Caitlin A Laverty(74) *Attorney, Agent, or Firm* — Lerner David LLP(57) **CLAIM**

The ornamental design for a tool holster, as shown and described.

DESCRIPTION

FIG. 1 is a front perspective view of a tool holster according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an environmental front perspective view thereof showing an example use thereof.

The broken lines shown in the drawings are for the purpose of illustrating environmental features that form no part of the claimed design.

1 Claim, 8 Drawing Sheets(56)
